CLAIM

The ornamental design for an outer housing of electrical connector, as shown and described.

DESCRIPTION

FIG. 1 is a top perspective view of an outer housing of electrical connector showing our new design with its two components separated;

FIG. 2 is a top plan view of an outer housing of electrical connector showing our new design assembled and on an enlarged scale;

FIG. 3 is a bottom plan view thereof;

FIG. 4 is a front elevational view thereof;

FIG. 5 is a rear elevational view thereof;

FIG. 6 is a right side elevational view thereof, the left side elevational view being a mirror image;

FIG. 7 is a cross-sectional view thereof taken along line 7—7 of FIG. 4;

FIG. 8 is a cross-sectional view thereof taken along line 8—8 of FIG. 4 and shown on an enlarged scale.

FIG. 1

FIG. 2

FIG. 3

FIG. 4

FIG. 5

FIG. 6

FIG. 7

FIG. 8
